UNITED STATES PATENT OFFICE.

ROBERT J. MARCHER, OF NEW YORK, N. Y.

IMPROVEMENT IN THE MANUFACTURE OF WOODEN MOLDINGS OR STRIPS FOR THE FRAMES OF MIRRORS, PICTURES, &c.

Specification forming part of Letters Patent No. **38,314**, dated April 28, 1863.

To all whom it may concern:

Be it known that I, ROBERT J. MARCHER, of the city, county, and State of New York, have invented a new and useful improvement in the manufacture of wooden moldings or strips for the frames of mirrors, pictures, &c.; and I do hereby declare that the following is a full, clear, and exact description of the same, reference being had to the accompanying drawings, making a part of this specification, in which—

Figure 1 is a face or front view of a piece of molding or strip constructed according to my invention; Fig. 2, a transverse section of the same, taken in the line *x x*, Fig. 1. Figs. 3 and 4, transverse sections of moldings or strips constructed according to the old plan.

Similar letters of reference indicate corresponding parts in the several figures.

This invention relates to an improvement in that class of moldings or strips for mirror and picture frames which are provided with an inner gilt portion or edge. This inner gilt portion or edge was originally produced by gilding or by applying metal, and then lacquering the same by means of a brush, the lacquered portion, of course, being directly by the side of or adjoining the other painted, stained, or colored portion of the molding or strip. The objection attending this plan consisted in the difficulty attending the forming, even by expert hands, of a neat junction of the gilded or metal and lacquered part with the colored part. With the utmost care in applying the gilt or metal and lacquer, there would always remain an uneven, rough, or crooked junction of the colored and the gilded or metal and lacquered parts which greatly impaired the neatness and finish of the frame. To obviate this difficulty, the inner portion of the molding or strip to be gilded or lacquered has been made separately from the other part, gilded or covered with metal and lacquered, and then fitted to said part when the frames were constructed. This plan, although overcoming the difficulty previously alluded to, was attended with additional labor—nearly double—in constructing the frames, as the inner gilded or metal and lacquered portion required to be cut and mitered together in the same way as the outer colored or stained part. Besides, the inner part would, if not well

seasoned, frequently warp and separate from the outer part and render the frame quite unsightly or much deteriorate it in appearance.

My invention consists in making the inner gilded or metal and lacquered part of the molding or strip separate from the outer part, as in the last-mentioned plan; but instead of fitting or abutting the inner against the outer part when the frames are manufactured, I construct the outer part with a groove or recess to receive the inner part, and secure said inner part to the outer part by that means, and either with or without glue or any suitable adhesive material or cement, so that when the moldings or strips are finished they will form one piece only, which will consequently only require to be cut and mitered together in the old or original way. By this means I obtain the advantage of the neat finish, as stated in the second plan, without the disadvantage of double labor and the liability of the separation of the two portions by warping, springing, &c.

To enable those skilled in the art to understand and construct my invention, I will proceed to describe it more fully as follows:

A represents the outer portion of the molding or strip, which is of wood prepared or coated, as usual, with a composition of whiting and size, and then colored or grained in imitation of rosewood or any other ornamental wood. This portion A has a groove or recess, *a*, made longitudinally in its inner edge, as shown clearly in Fig. 2. This groove or recess is made of such dimensions that it will receive the inner gilded or metal and lacquered portion B of the molding or strip, the portion B being made separately from A, gilded or covered with metal and lacquered, and then fitted in the groove or recess *a*, and, if desired, secured therein by glue or any proper cement or adhesive substance. The two parts A B, thus fitted and secured together, form or complete the entire molding or strip, and the same may be cut and mitered together to form a frame in the same way, and without any more labor and expense than by the old plan, in which the molding was composed of one piece only. The groove or recess *a* effectually retains the portion B in its place, and prevents said portion from springing or separating from the portion A.

In Fig. 3 the original molding is shown, *b* being the outer colored portion, and *c* the inner lacquered portion. In Fig. 4 the improvement on the original plan is shown, *d* being the outer colored portion, and *e* the inner lacquered portion, the latter being made separately from the former, and then in the making of the frame simply abutted or placed against a lip, *f*, at the inner edge of *d*, the portion *e* being required to be cut and mitered together in the same way as *d*, thereby causing double work in the manufacturing of the frames, while the portion *e*, when the frames are manufactured, is liable to spring or separate from *d*.

Although I suggested the application of glue or other suitable adhesive material or

cement in holding the two portions *A*, *B* together, I do not wish to be understood as confining myself to its use, as it may be dispensed with if the portion *B* is made to fit snugly or properly in the groove or recess in the portion *A*.

Having thus described my invention, what I claim as new, and desire to secure by Letters Patent, is—

A molding or strip for the manufacture of picture and other frames, constructed of two parts or portions, *A*, *B*, connected together in the manner substantially as herein set forth.

ROBT. J. MARCHER.
